Primary Examiner — Jennifer L Watkins(74) *Attorney, Agent, or Firm* — Fross, Zelnick, Lehrman,
& Zissu, P.C.; Charles T. J. Weigell, Esq.(57) **CLAIM**

The ornamental design for a boot, as shown and described.

DESCRIPTIONFIG. 1 is a front perspective view of the boot showing my
new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines depicting portions of the shoe sole show
portions of the boot that form no part of the claimed design.**1 Claim, 7 Drawing Sheets**(56)
